UNITED STATES PATENT OFFICE

FRANCIS X. A. KREIL, OF ALTADENA, CALIFORNIA

MONOLITHIC HOLLOW CONCRETE-WALL CONSTRUCTION

Application filed September 19, 1927. Serial No. 220,368.

This invention relates to wall constructions and more particularly to forms or cores that may be used in forming a wall to cast spaces therein for the purpose of lightening the 5 load thereof.

In wall constructions of buildings between inside pillars, it is often necessary to lighten the load of such wall. Tile and brick have been used to accomplish this end, but due to 10 likelihood of earthquakes, such tile and brick is not satisfactory, whereas concrete walls are acceptable to avoid dangers that otherwise might arise as a result of subjecting such wall to tremors due to earthquakes.

15 Heretofore, wooden forms have been used to form an air space in a concrete wall to be lightened, but if such form is left in the wall it is likely to swell and crack the wall and if such wooden form or core is withdrawn 20 from the wall likelihood of cracking the wall is also prevalent.

An object of my invention is to provide a 25 novel and improved form or core for use in constructing a hollow concrete wall and which will be inexpensive, light and not likely to swell if left in the wall and thereby eliminate the objectional feature of the use of wooden forms.

Another object is to provide a novel and 30 improved form or core by means of which concrete walls may be poured at one time from floor to top whereby cold joints may be eliminated which occur in the use of metal forms that generally permit pouring at one 35 time of the concrete to a depth of about three or four feet.

Another object is to provide a novel form 40 for creating perfect vacuum spaces in building walls.

Another object is to provide novel, inexpensive means whereby a concrete wall may be provided with hollow spaces without likelihood of cracking the wall by the means 45 employed in its construction.

Other objects, advantages and features of 50 invention may appear from the accompanying drawing the subjoined detail and the appended claims.

The accompanying drawing illustrates the

invention in some of the forms I at present deem preferable.

Figure 1 is a front elevation of a concrete wall constructed with air spaces formed in accordance with my invention. Parts are 55 broken away to illustrate interior construction.

Fig. 2 is a horizontal transverse section of the wall shown in Fig. 1.

Fig. 3 is a fragmental perspective view of 60 a form or core constructed in accordance with my invention.

Fig. 4 is a fragmental perspective view of a modified form of core constructed in accordance with my invention. 65

My invention comprises the combination of a concrete wall A having imbedded therein an inexpensive form or core 1 that is adapted to provide in the wall A a perfect 70 vacuum air space a.

The core or form 1 is preferably made of a single sheet of ribbed metal lath or light gauge sheet metal which is bent into the desired shape with its meeting edges bent to form tongue and groove fastening means in the form of hooks 2 and 3 that engage with each other to maintain the edges in fixed relation to each other. The hooks 2 and 3 are bent inward from the outer surface of the 75 form, so as to leave the same unobstructed. 80

The form 1 may be of a length equal to the distance between the floors b and c of the building and may also be of shorter lengths to extend from the a floor b to the under side of a window d. As shown in Figs. 1-3, the 85 stiffening members in the form of channel irons 4 are secured to the outside of the end walls of the form 1 adjacent the corners thereof by means of the wires 5, which are extended through said end walls from the inside around the outside of said channel irons and tied together at their ends. Said channel irons reinforce and stiffen the form at its 90 corners. 95

Heavy wire hoops 6 are slipped over the form and secured thereto at suitable distances apart, as for example, about eighteen inches or two feet, by means of the wires 7 which extend over said hoops through the side and 100

end walls of the form, at the corners thereof, and are tied together at their ends.

5 Seep holes 8 are provided in the lower end of the form, and through the wall, and through which excess water may be drained, and caps 9, preferably of metal, are fitted on the upper ends of the forms.

10 In the modification of my core or form 1 shown in Fig. 4, the stiffening members are in the form of angle irons 10 which are substituted for the channel irons 4 and said angle irons are placed over the corners of the form and tied to the ends of the core by tie wires 11, which are extended through the side 15 and end walls of the form around said angle irons and tied together at their ends.

20 In practice, my form is placed within the usual outside wall form 12, and blocks *e* space the form 1 from the wall form 12, and maintains it centrally therein. Concrete 13 is poured within the wall form around form 1 from top to bottom thereon, thus eliminating cold joints between pourings. The spacing blocks *e* are withdrawn as the concrete is 25 poured. The concrete mix may be wet or dry, preferably the consistency of mortar. The seep holes 8 are closed or sealed when the outside forms are stripped, thus providing a perfect vacuum space throughout the wall.

30 I claim:

35 1. A form for walls, said form comprising a sheet of metal bent into the shape of the form and having its meeting edges interlocked, and stiffening means secured to the form adjacent the corners thereof.

40 2. A form for walls, said form comprising a sheet of metal bent into the shape of the form and having its meeting edges interlocked, and reinforcing irons secured to the ends of the form adjacent the corners thereof.

45 3. A form for walls, said form comprising a sheet of metal bent into the shape of the form, stiffening members secured to the ends of said form adjacent the corners thereof, and heavy wire hoops extending around the form at suitable distances apart.

50 4. A form for walls, said form comprising a sheet of metal lath bent into the shape of the form, means holding the edges of said lath in fixed position, and stiffening means secured to the form adjacent the corners thereof.

55 5. A form for walls, said form comprising a sheet of metal lath bent into the shape of the form and having its meeting edges interlocked, spaced heavy wire hoops encircling the form, tie wires to secure said hoops to the form, stiffening members extending longitudinally of said form, and tie wires securing said members to said form.

60 6. A form for walls, said form comprising a sheet of metal lath bent into the shape of the form, means encircling said form at suitable distances apart to hold the form together; means for securing the hoops in position on the form; channel irons extending along the

form, and means to secure the channel irons to the form.

65 7. A form for walls, said form comprising a sheet of metal lath bent into rectangular shape and having its meeting edges secured together, reinforcing irons at the ends of the form adjacent the corners thereof, and tie wires for tying the irons to the form.

70 8. A wall construction of concrete having therein cores to form air spaces; said cores comprising a sheet metal lath bent into the shape of the core; means closing the top of the cores; seep holes at the bottom of the core adapted to be closed; and said cores having stiffening members secured to its sides.

75 9. A core for concrete walls and which comprises a strip of metal lath bent into the shape of the core; means for holding the edges of said lath in fixed position; stiffening members secured to the sides of said core; heavy wire hoops encircling said core at suitable distances from each other, and means closing the top of said core; there being seep holes at the bottom of said core adapted to be closed after drainage.

80 In testimony whereof, I have hereunto set my hand at Los Angeles, California, this 10th day of September, 1927.

FRANCIS X. A. KREIL.
